GARMENT HANGER MAKING MACHINE

Louis Brownstein, Brooklyn, N. Y., assignor to
Standard Hanger Co., Inc., Brooklyn, N. Y., a
corporation of New York

Application November 27, 1935, Serial No. 51,732

20 Claims. (Cl. 140—71)

This invention relates to machines for making wire garment hangers and relates particularly to machines for making such hangers automatically from rolls of wire fed to the machine.

5 My invention contemplates the provision of a machine capable of operating at high speed to cut off lengths of wire of the proper size alternately from a number of rolls of such wire, to bend and twist the wire to form a complete hanger, and to 10 eject the finished hanger from the machine.

My invention further contemplates the provision of means for cutting off a length of wire from a roll and partly forming a garment hanger from said length and during the formation of one 15 hanger from said length, cutting off and positioning another length of wire from another roll preparatory to the formation of the next hanger.

My invention further contemplates the provision of simple and efficient means for alternately 20 drawing off and severing equal lengths of wire from a pair of rolls of such wire, preparatory to the bending of such lengths of wire into hangers.

My invention further contemplates the provision of simple and efficient means for forwarding 25 the lengths of wire cut off from the rolls into position for the bending and twisting thereof, and of efficient means for rapidly bending up the lengths so cut and positioned into garment hangers.

The various objects of my invention will be 30 clear from the description which follows and from the drawings, in which

Fig. 1 is a front elevation of my new machine.

Fig. 2 is a vertical section thereof, taken on the line 2—2 of Fig. 1.

35 Fig. 3 is a top plan view and horizontal section, taken on the line 3—3 of Fig. 1.

Fig. 4 is a vertical section of part of the machine on an enlarged scale and taken on the line 4—4 of Fig. 3.

40 Fig. 5 is an enlarged top plan view and partial horizontal section of the wire feeding shuttle.

Fig. 6 is a vertical section of said shuttle, taken on the line 6—6 of Fig. 5.

45 Fig. 7 is a vertical section of the same, taken on the line 7—7 of Fig. 5.

Fig. 8 is a vertical section of the wire elevating and positioning means, taken on the line 8—8 of Fig. 1.

50 Fig. 9 is a front elevation of the wire bending means.

Fig. 10 is a vertical section of the second bending means, taken on the line 10—10 of Fig. 1.

55 Fig. 11 is a vertical section and side elevation of the means for positioning the bent hanger prior

to the twisting of the neck thereof, and for ejecting the finished hanger from the machine.

Fig. 12 is a horizontal section of the operating mechanism for the twisting means, taken on the line 12—12 of Fig. 2.

Fig. 13 is a horizontal section of the twisting jaws, taken on the plane indicated by the line 13 of Fig. 2.

Fig. 14 is an elevational view of the length of wire as it appears after it has been cut off preparatory to the bending thereof.

Fig. 15 is a similar view of the length of wire after the first bends have been made therein.

Fig. 16 is a similar view of the length of wire after the second bends have been made therein.

Fig. 17 is a similar view of the length of wire after the hook has been bent from the projecting end thereof.

Fig. 18 is a similar view of the finished hanger after the neck thereof has been twisted to secure 20 an end of the length of wire to the neck of the hanger.

Fig. 19 is a perspective view of the anvil die for the third bend and of the auxiliary hanger-supporting slides.

Fig. 20 is a diagrammatic front elevation of the 25 pair of wire rolls, the shuttle and the wire cut off means, showing how a length of wire is drawn off from the rolls of wire alternately.

In the practical embodiment of my invention 30 which I have illustrated by way of example, it is intended that the machine operate at high speed and economically with a minimum of attention on the part of the operator. I therefore provide two separate and independent rolls 20 and 21 (Fig. 35 20) of wire and further provide means preferably in the form of a shuttle for drawing a length of wire from each of the rolls 20 and 21 alternately and for cutting off the length of wire so drawn from the rolls to the proper length. I also provide means for rapidly operating upon the length of wire so cut to form all the bends in the wire during the time that the next length of wire is being drawn from the roll by the shuttle and severed therefrom. I also provide a station spaced 40 from the bending stations, at which the neck of the hanger is twisted while the succeeding length of wire is being bent.

My machine therefore preferably includes 50 means for alternately drawing off and severing from the pair of rolls of wire, predetermined lengths of such wire, means for forming the bends in one of the lengths while the succeeding length of wire is being drawn off a roll and severed. The machine also includes preferably, means for 55

transferring the bent wire to another station where the twisting operation upon the neck of the hanger is performed during the time that the next succeeding length is being arranged in 5 the proper position and bent.

Referring now to Figs. 1, 2, 3, 5, 6 and 7, I have there shown a shuttle designated generally by the numeral 22 and movable across the machine first in one direction and then in the other. Said 10 shuttle serves to grip the severed end of each roll of wire alternately during its movement and to draw off from the roll the desired length to be thereafter bent into the hanger. Said shuttle further cooperates with a pair of wire severing 15 cutters 23 and 24 which are set into operation alternately at the extreme end of each stroke of the shuttle.

As shown, the shuttle comprises a gripper support 25, (Fig. 5) provided with a recess 26 (Fig. 20 6) for the reception of the fixed guide bar 27, which bar is suitably supported as by means of the brackets 28 (Figs. 1 and 2) secured to the frame 29 of the machine. A suitable gib 30 removably secured to the support 25 as by means 25 of the bolts 31, encloses the lowermost edge portion of the guide bar 27 and serves to adequately mount the shuttle for proper sliding movement on the guide bar.

The shuttle is reciprocated by means of the 30 continuously moving chain 32, (Figs. 1, 2 and 3), driven by the sprocket wheels 33 and 34. The sprocket wheel 33 is mounted on a suitable shaft rotating in the bearing 35 in a clockwise direction as viewed in Fig. 3. The sprocket wheel 34 35 is mounted on a suitable shaft rotating in the bearing 36 at the right end of the machine, said shaft carrying the gear 37 meshing with the gear 38 on the main drive shaft 39 (Fig. 3). The main drive shaft 39 extends rearwardly of the machine 40 and at its rear end, carries the pulley 40 which is rotated by suitable connections to a source of power not shown. It will be seen that on the continuous rotation of the pulley 40, the chain 32 is continuously moved in the direction of the 45 arrow of Fig. 1.

In order that the motion of the chain be imparted to the shuttle 22 to reciprocate said shuttle, a link 41 is pivoted at one of its ends 42 to the chain and at the other of its ends 43, is pivoted to the shaft 44 mounted in the shuttle support 22. It will be understood that as the end 42 of the link is carried around the sprocket wheel 33 from the lower part of said wheel to the upper part thereof, the shuttle is brought to rest 55 momentarily at the extreme left end of its movement, and the movement thereof in the opposite direction, that is, toward the right, is begun. It is just prior to the time that the direction of movement of the shuttle 22 is changed that the 60 length of wire drawn to the left by the shuttle is severed from the roll 21 and raised into the position for the bending thereof.

Similarly, as the shuttle approaches its limiting position at the other end of the machine, 65 the length of wire drawn off the roll 20 is severed.

The means for gripping the severed end of the wire, for drawing off a length of wire from the roll, and for severing the length thus drawn off will now be described.

70 Pivotaly mounted on the reciprocating supporting member 25, forming part of the shuttle, as by means of the upright studs 45 and 46 (Fig. 5) are the respective wire gripping jaws 47 and 48, said jaws being swingable in a horizontal 75 plane on said studs. At its rear, the jaw 47 is

provided with an inclined bevelled face 49 cooperating with the oppositely bevelled face 50 of the relatively stationary wire gripping member 51 to grip the wire 52 at the proper time, said faces 49 and 50 providing a recess 53 therebetween for the ready entrance thereto of the free end of the wire 52. The gripping member 51 is suitably secured to the support 25 as by means of the screws 54. To normally urge the jaw 47 into the wire gripping position thereof, one end of the compression spring 55 is inserted into a suitable recess in the jaw and the other end of the spring is inserted into a corresponding recess in the member 56 which is fixed to the support 25 and forms a part thereof.

It will be seen that the jaw 47 is normally rotated by the spring 55 about its pivot 45 into the position wherein the rear face of said jaw is brought sufficiently close to the front face of the member 51 to permit the wire 52 to be adequately gripped therebetween, and that when the jaw 47 is rotated in a clockwise direction as viewed in Fig. 5 against the action of the spring 55, the wire gripping face of the jaw is carried away from the cooperating face of the member 51 a sufficient distance to release the wire gripped therebetween. Such release of the jaw occurs preferably just before the shuttle 22 is at the extreme right end of its path of movement after having drawn the wire 52 toward the right from the roll 30 20 a predetermined distance so that the proper length of such wire may be severed from the roll.

The jaw 48 is provided with a bevelled face 57 similar to the face 49 of the jaw 47, and with a spring 58 similar to the spring 55 and operating 35 in the same manner. To hold the jaws down on the support 25, a cross member 59 mounted on the studs 45 and 46 is provided, said cross member being removably secured to the support 25 as by means of the bolts 60.

When the shuttle is at the extreme right end of its movement, the rotary cutter 23, provided with a cutting edge 62 and mounted on the shaft 63, is operated to sever a predetermined length of the wire 52. The cutter shaft 63 is mounted on the cutter block 64 which is in turn slidably mounted on the guide bar 27 as by means of the gib 65. At the end of the shaft 63 opposite from that on which the cutter 23 is mounted, a cam lever 66 is fixed, said lever being pulled by the spring 67 in the proper direction to position the cutter 23 out of the way of the wire. Said cam lever 66 is provided with an extension 68 having a cam-engaging surface 69 adapted to be engaged by the cam 70 on the shaft 71. The shaft 71 is continuously rotated through the bevel gear 72 mounted on said shaft, which gear engages the bevel gear 73 on the front end of the shaft 74, the shaft 74 being in turn rotated through the gear 75 meshing with the gear 76 on the shaft 39. 50 55 60

Extending from the cutter block 64 is the spring-holding rod 77 passing through the extension 78 on the guide bar 27 (Figs. 1 and 3) and provided at its outer end with the adjustable stop nuts 79. The spring 80 is interposed between the extension 78 and the cutter block 64 65 and is compressed when the cutter block is moved along the guide bar 27 under the action of the shuttle 22. A cushion 81 of suitable resilient material such as rubber or the like is secured to the cutter block 64 and is arranged to be engaged by a projection as 82 on the shuttle during the last part of the movement of the shuttle toward the left. The wire 52 is passed loosely through a suitable opening 83 in the cutter block and in the 70 75 80 85 90 95

cutter lever 66 and before the severing thereof is gripped between the jaw 47 and the member 51 (Figs. 5 and 20) during the movement of the shuttle toward the right.

It will be understood that the cutter block together with the cutter and the cutter lever carried thereby and above described are mounted on and have a limited longitudinal movement on the left end of the guide bar 27, and are used in connection with the severing of a length of wire 52 from the roll 20, being also used in connection with the gripping of the severed end of the roll by the shuttle when the shuttle is at the extreme left end of its movement. However, a similar cutter block 83, cutter 24 and cutter lever 84 are slidably mounted at the right end of the guide bar 27 and being similar in all respects to the first-mentioned cutter block and its parts, the above description of the former will suffice for both.

The cam 70' on the shaft 71 is similar to the cam 70 and operates the cutter lever 84 in a similar manner.

In the position of the parts shown in Figs. 1 and 3, a length of wire 85 has been drawn by the shuttle off the roll 21 of wire and has been released by the shuttle, and the shuttle is in its position at the end of its movement toward the left. In this position, the projection 86, which extends forwardly from the upper part of the jaw 48, has been and still is engaged by the fixed adjustable stop 87. Said jaw is therefore swung about its pivot 46 and has released the wire 85. The shuttle, in the last part of its movement toward the left, has engaged the cushion 81 and has moved the cutter block 64 with it toward the left against the action of the spring 80, thereby exposing the right end portion of the wire 52 at the right beyond the cutter block 64. The severed end portion of the wire has therefore entered the recess 53 and forced itself between the jaw 47 and the member 51 to be gripped therebetween under the action of the spring 55. The cutter 24 is now rotated by the cam 70' to sever the length of wire 85 before the shuttle 22 starts on its return movement toward the right with the wire 52 gripped therein. The point of release of the wire end by the shuttle being determined by the adjustment of the stop 87, the length of the severed wire may be accurately predetermined.

It will be understood that the wire 52 as it comes from the roll 20 is straightened by suitable straightening rollers designated generally by the numeral 88 or by a suitable straightening machine of any well known type. Similarly, the wire 85 has been straightened by the straightening machine or rollers 89 prior to its passage through its cutter block 83 so that the severed lengths of wire are sufficiently straight to be properly operated on by the various instrumentalities for advancing and bending the lengths.

As the shuttle 22 moves toward the right with the wire 52 gripped thereby, a predetermined length of said wire 52 is drawn off the roll 20, the precise length being dependent upon the adjustment of the jaw stop 90, which is carried by a suitable bracket 91 secured to the frame of the machine and which operates to engage the lower extension 92 of the jaw 47 at the proper time to open said jaw and to release the wire 52 preparatory to the severing thereof by the cutter 23 through the operation of the cam 70.

The jaw stop 87 is carried by an arm 93 secured to the chain guard 94. The upper chain guard

94 together with the lower chain guard 95 are supported as by means of the brackets 96, 97 secured to the machine frame and serve to maintain the chain in its proper operative position at all times.

It will be seen from the above description that the shuttle in its alternative movements toward the right and toward the left first draws a length of wire 52 from the roll 20 and preparatory to its return movement toward the left, said length 10 of wire is severed by the cutter 23 and the severed length 52 is released, whereafter as the movement of the shuttle in the same direction is completed, it grips the end of the length of wire 85 and draws off a predetermined length of such 15 wire from the roll 21, which length is again severed and the operation repeated whereby the proper straightened lengths of wires are alternately drawn off from the rolls and positioned ready for the bending and twisting thereof into 20 hangers.

The means for forwarding the severed length of wire into bending position will now be described.

Just prior to the severing of each length of 25 wire, means are positioned for engaging the wire when severed and for forwarding said wire into position for the bending thereof. Said means comprises a plurality of similar spaced wire-engaging fingers 100, each provided with a wire- 30 receiving recess 101. Since the fingers are similar in construction and operation, a description of one of said fingers and of the means for operating it will suffice for all. The wire supporting finger 100, best shown in Fig. 8, is pivoted as 35 at 102 to the finger lever 103. Said lever 103 is pivoted as at 107 to a suitable bracket secured to the frame of the machine and is provided with a cam roller 104 engaging the surface of the cam 105 mounted on the shaft 71. The 40 spring 106 connected to the finger 100 and to the lever 103 urges said finger toward its uppermost position as viewed in Fig. 8 and against the pin stop 108. The cam 105 is so shaped that the pivot 102 and the finger are normally 45 in their uppermost positions. In said position, the extension 100' of the finger engages a face of the frame 29, thereby insuring against movement of the intermediate fingers 100 under the stresses of the bending operations upon the wire 50 later to be described and serving to hold the fingers into their uppermost positions to maintain the intermediate portion of the wire against flexing.

When, however, the length of wire is about 55 to be severed by either of the cutters 23 or 24, then the roller 104 enters the depressed portion of the cam 105 whereby the finger lever and the finger carried thereby swing downwardly about the lever pivot 107 to carry the finger below the 60 length of wire and into the position wherein the wire when severed rests in the recess 101. Immediately after the wire has been severed, the lever 103 and the finger 100 are swung upwardly to carry the length of wire into the position 65 wherein the first bend is made therein, as shown in Fig. 8. In this position, the wire touches the bottom of the anvil shaft 109 and lies forwardly of the transfer finger 110. Said transfer finger is bent partly around the anvil and provides a 70 stop face or shoulder against which the wire may be bent, said finger when moved relatively to the anvil shaft also serving to eject the bent wire at the proper time from the bending station thereof to the neck twisting station, as will 75

be more fully explained hereinafter. The finger 110 is mounted on the shaft 111, which shaft is secured at its rear end to the plate 112 for forward and rearward movement therewith as a unit and relatively to the rotatable anvil shaft 109. The anvil shaft 109 extends rearwardly to a point near the rear of the machine (Figs. 2 and 3), and is there provided with a pinion 113.

It being understood that a pair of first bends 114 and 114' are made simultaneously in the length of wire, it may be stated that the mechanism for performing the first bend at the right of the hanger is substantially identical with that just described for performing the first bend at the left of the hanger.

The right hand first-bend mechanism comprises the anvil shaft 115 similar to the anvil shaft 109, the finger 116 similar to the finger 110, and the finger shaft 117 similar to the shaft 111. At the rear end of the anvil shaft 115 is mounted the pinion 118 similar to the pinion 113. On the front end of the anvil shaft 109 is fixed the crank 119 carrying at its outer end the rotatable grooved roller 120 having the circumferential wire-receiving groove 121 therein. Similarly, the anvil shaft 115 carries at its front end, the crank 122 which in turn carries the grooved roller 123.

In order to rotate the anvil shafts 109 and 115 simultaneously to swing the cranks 119 and 122 and thereby to carry the straight wire held by the fingers 100 around the respective anvil shafts to form the first bends in the wire, the anvil shaft pinions 113 and 118 are simultaneously rotated in opposite directions at the proper time. To effect such rotation of the pinions, the rack bar 124 is provided with teeth 125 in its lower edge for engaging the pinion 113, the extension 126 of said bar being provided with rack teeth 127 in its upper edge engaging the pinion 118. The rack bar 124 is held in engagement with the pinion 113 by means of the roller 128 pivoted to the machine frame, while the extension 126 is similarly held in engagement with the pinion 118 by means of a similar roller 129. Secured to the rack bar 124 as at 130 is the short link 131, the other end of said link being connected to the oscillatory crank 132, (Figs. 3 and 4), the crank 132 being pivoted at its lower end on the shaft 133 (Figs. 3 and 4).

The crank 132 also carries the cam roller 134 engaging the cam 135 on the shaft 136. Said shaft 136 carries at its rear end a gear 137 meshing with the gear 75 and rotated thereby continuously.

It will be seen that during the operation of the machine, as the shaft 136 is rotated, the crank 132 will be oscillated, thereby reciprocating the rack bar 124 and its extension 126 and rotating the pinions 113, 118, and the anvil shafts 109, 115 respectively carried thereby to carry the rollers 120, 123 and the wire end portions resting in the respective grooves thereof around the anvil shafts to form the bends 114, 114' and to bend the wire into the form shown in Fig. 15.

The left inclined portion 138 of the wire is shorter than the right portion 139, the portion 138 however, lying below the bending striker 140 (Fig. 9) while the portion 139 similarly lies below the striker 141. During the bending of the portion 139 (see Fig. 10), said portion engages the bevelled top 250 of the retracted striker and slides downwardly thereon as the bending proceeds until it slides off the striker top, whereby

the portion 139 becomes positioned below the hook bending pins 186 and 182 later to be described, as shown by the dot-dash lines of Fig. 1.

Said strikers 140 and 141 are simultaneously operated to form the second and third bends in the wire. The second bends 142 and 143 are formed by bending the wire about the movable second bend anvils 144 and 145 respectively, while the third bends 146 and 147 are simultaneously formed by the strikers in cooperation with the fixed die 148 (Fig. 19). The rear ends of the second bend anvils 144 and 145 are secured to the plate 112.

Each of said anvils is provided with a reduced front end, thereby forming shoulders 149 and 150 respectively, against which shoulders the wire portions 138 and 139 respectively rest after the formation of the first bends 114, 114' (Fig. 10). The striker 140 is mounted for reciprocatory movement in the fixed guide 151 (Figs. 1 and 9). At its upper end, said striker is connected by the link 152 to the crank 153 on the shaft 154. Near the rear end of said shaft 154 is carried the shorter crank 155 (Fig. 4) to the outer end of which is secured one end of the connecting rod 156, the other end of said rod being secured to one end of the bell-crank-lever 157 pivoted on the anvil shaft 109. The roller 158 carried by said bell-crank-lever engages the cam 159 on the shaft 136, said roller being held in contact with the cam by means of the spring 160 fixed at one end as 161 to the machine frame and at its other end as 162 fixed to the crank, said spring urging the crank 155 in a counter-clockwise direction as viewed in Fig. 4 and thereby normally maintaining the striker 140 in its retracted position.

The means for operating the striker 141 being substantially identical with the means just described for operating the striker 140, the description thereof need not be repeated except to say that the cam 159' for operating the striker 141 is mounted on the shaft 14.

The lower end of each of the strikers is preferably provided with a recess 163 into which the end portions 138 and 139 of the wire are respectively received. As the striker 140 moves downwardly in its guide under the action of the cam 159, the wire 138 is engaged and bent around the anvil 144 and against the shoulder 149 thereof, the wire being carried past the anvil and into the recess 164 of the die 148, said recess being provided with an upright wall 165. The end part 166 of the wire is bent into substantially upright position by the striker 140 and the wall 165.

As to the right end portion 167 of the wire, said end portion is bent by the striker and die 148 into a position wherein it rests against the surface of the hook-forming anvil and below the hook-forming rollers 180 and 182, as previously mentioned. The hook-forming anvil comprises the hollow outer shaft 168 carrying at its rear end, the pinion 169 (Figs. 2, 4, and 11). Rotatably mounted inside of the outer shaft 168 is the inner shaft 170 extending toward the rear of the machine and there provided with the pinion 171. Meshing with the pinion 169 on the outer shaft 168 is the rack bar 172 guided in its reciprocatory movement by the roller 173. The lever 174 pivoted at one end to the shaft 133 and at its other end, connected to the rack bar 172, carries a roller 175 engaging the cam 176 on the shaft 136.

It will be seen that on the operation of the machine, the lever 174 is oscillated, thereby caus-

ing reciprocation of the rack bar 172 and consequent oscillation of the outer hook-forming anvil shaft 168 at the proper time. Similarly, the pinion 171 on the shaft 170 is engaged by the rack bar 177 oscillated by the lever 174 through the engagement of the roller 175 of said lever with the cam 176 on the shaft 74. It will thus be noted that when the outer shaft 168 is rotated in one direction, the inner shaft 170 is rotated in 10 the opposite direction.

Carried by the front end of the outer shaft 168 is the hub 178 carrying the pin 179 on the projection 180 thereof (Figs. 1, 9 and 11). Similarly, the hub 181 is carried by the front end of the inner shaft 170 and is provided with the bending pin 182. Said pin 182 is swung by the rack bar 177 in the direction of the arrow of Fig. 9 to form the neck or lowermost bend 183 (Fig. 17) in the hook 184 of the hanger, while the pin 180 is operated by the rack bar 172 to bend the hook 184 from the end portion of the wire about the hub 181, said pin 180 being moved in the direction of its arrow and in the direction opposite to that of the movement of the pin 182. It will be understood that on the return movement of the racks, the pins 180 and 182 are moved back to the initial positions thereof shown in Fig. 1.

All of the bends having thus been completed, the thus bent hanger is moved forwardly into position for the twisting operation upon the neck of the hanger. The means for so moving the hanger into the twisting position will now be described.

It being remembered that the second bend anvil shafts 144 and 145 as well as the finger shafts 111 and 117 are secured at their rear ends to the plate 112 and that the hanger rests against the shoulders 149 and 150 of the shafts 144 and 145 and against the fingers 110 and 116, it will be seen that movement of the plate 112 forwardly will move the anvil shafts 144 and 145 and the fingers 110 and 116 as a unit to move the bent hanger off the hook-forming hub 181 and toward the front ends of the first bend anvil shafts 109 and 115 into the position shown in Figs. 2 and 11.

Such movement of the plate 112 and the shafts carried thereby is caused by the lever 185 which is connected to the plate 112 by the link 186 and the plate projection 187. The lever 185 is pivoted at its lower end (Fig. 4) on the pivot shaft 188 carried by a suitable bracket 189 mounted on the shafts 133 and 209. A cam roller 190 is carried by the lever 185 intermediate its ends and engages the face of the cam 191 on the shaft 136 (Figs. 3 and 4), the spring 192 (Fig. 3) serving to maintain the roller in engagement with the cam.

It will be seen that during the rotation of the shaft 136, the lever 185 is oscillated at the proper time to carry the plate 112, the parts carried thereby, and the bent hanger into the twisting position shown in Figs. 2 and 11. On such forward movement of the plate 112, however, the hanger previously arranged in the twisting position and which had previously been twisted, is forwarded on to the fixed tubular hanger support 193. Said support is carried by the arm 194 (Figs. 1 and 2), suitably secured at its lower end to the machine frame and bent to clear the hanger 70ers accumulating on the support 193.

The means for forwarding the twisted hanger on to said support on the forward movement of the plate 112 comprises a pair of trigger latches 195, said latches being arranged coaxially of the shafts 144 and 145, respectively, and being similar

in construction, a description of one will suffice for both. A plate 196 is suitably secured in a groove in the lower part of each of the shafts 144 and 145 and extends forwardly thereof. At its forward end, the plate 196 carries a grooved bar 5 197, in the groove of which is pivoted the latch 195 for swinging movement in a vertical plane and against the action of the spring 198 (Fig. 11). The rear end of the upper surface of the latch is bevelled and terminates in a shoulder 10 adapted to grip the hanger. It will thus be seen that on the forward movement of the plate 112, the latches 195 grip the twisted hanger at a point adjacent the bends 142 and 143 thereof and forward said hanger from the twisting position on to 15 the support 193 while the next hanger is being forwarded by the shoulders 149 and 150 and the fingers 110 and 116 along the die 148 into the twisting position.

After the hanger to be twisted has been positioned as above described, the lever 185 is oscillated by its cam to retract the plate 112, the shafts 144 and 145 and the fingers 110 and 116 into the position where the bending operation may be performed upon the next hanger while the 25 twist in the hanger just forwarded into twisting position is being performed. Part of the supporting means for the hanger to be twisted having thereby been removed, it becomes advisable to additionally support the hanger to permit the 30 twisting operation to be properly carried out.

As shown particularly in Figs. 1, 2, 11 and 19, said auxiliary or additional supporting means 35 takes the form of a pair of reciprocatory slides 200 and 201, each sliding in an upright groove in one of the upright faces of the die 148 and each having a suitable recess 202 in the upper edge thereof for engaging the substantially horizontal portions 203 and 204, respectively, of the hanger (Fig. 18).

The slidable hanger supports 200 and 201 are connected at their lower ends to the lever 205, one end of which is interposed between said slides and the other end of which is connected to the connecting rod 206, said lever being pivoted as 45 at 207 to the frame of the machine (Figs. 2, 3, 4 and 11). At its lower end, the connecting rod 206 is pivoted to the bell-crank-lever 208 which is mounted on the shaft 209 and one arm of which carries the roller 210, engaging the cam 211 on 50 the shaft 74. It will be seen that on the rotation of the shaft 74, the bell-crank-lever 208 is oscillated at the proper time during the retraction of the plate 112 to lower the connecting rod 206 and thereby to oscillate the lever 205 and to raise the 55 supporting slides 200 and 201 into the proper position to support the untwisted hanger in the twisting position, the parts 203 and 204 of the hanger entering the recesses 202 of the slides.

The mechanism for performing the twisting 60 operation upon the wire parts 166 and 167 to secure said parts together to form the twist 199 (Fig. 18) will now be described.

Said mechanism includes the bearing 212 (Fig. 2) secured to the frame of the machine and supporting the twister sleeve 213 for vertical reciprocation therein. Said sleeve is provided with an elongated pinion portion 237 above which is secured the block 214 suitably held against rotation, and the collar 215. The lower end of the 70 sleeve 213 is grooved for the arrangement therein of the gripping jaws 216 and 217 which are pivoted to the sleeve as at 218 and 219, respectively. In a suitable circumferential recess around the jaws and the sleeve is arranged the 75

ring spring 228 which tends to draw the upper ends of the jaws toward each other and thereby to spread the lower ends of said jaws apart, the upper ends of the jaws being suitably rounded 5 for the purpose soon to be described. The rod 221 is slidably mounted for reciprocation within the sleeve 213 and at its lower end, terminates in a conical portion 222 adapted to enter between the rounded upper ends of the jaws to spread said 10 ends apart and thereby to cause the lower ends of the jaws to close upon the hanger. The pin 223 projects horizontally from the rod 221 into the vertical slot 224 in the sleeve and serves to limit the relative movement of the rod and sleeve 15 in either direction.

Movement of the sleeve 213 in a downward direction is limited by the adjustable stop bolt 225 secured to the block 214 and adapted to engage the stop block 226 secured to the upper face of 20 the bearing 212. The compression spring 227 is interposed between the collar 215 and the connecting member 228 at the upper end of the rod 221. Said connecting member connects said rod to the links 229 which are in turn connected 25 to the lever 230 pivoted to the bracket 231 as at 222. The left end of said lever 230 as viewed in Fig. 2 is connected to the upper end of the rod 233, the lower end of said rod being in turn connected to the bell-crank-lever 234 (Fig. 4) carrying 30 the roller 235 which engages the cam 236 on the shaft 74.

It will be understood that on the rotation of the shaft 74, the bell-crank-lever 234 is oscillated 35 at the proper time to reciprocate the rod 233 and thereby to oscillate the lever 230, as a result of which the rod 221 is reciprocated at the proper time. That is, after the hanger has been positioned as hereinbefore described in the position wherein it is to be twisted, the rod 221 is moved 40 downwardly together with the sleeve 213 as a unit, it being understood that the pin 223 is at the upper end of the slot 224 and that the conical portion 222, at the upper end of the slot 224 and that the conical portion 222, at the lower end 45 of the rod, is above the jaws, whereby said jaws are held open and pass about the hook part 184 of the hanger, the spring 227 serving to transmit the motion of the rod to the sleeve. When, however, the sleeve and the block 214 have reached 50 the position wherein the jaws 216 and 217 are arranged on opposite sides of the hanger hook and of the upper ends of the parts 166 and 167 of the hanger, the stop 225 strikes the stop block 226, thereby halting further downward movement of 55 the sleeve 213. Continued motion of the lever 230, however, causes further downward movement of the rod 221 against the action of the spring 227, thereby projecting the lower conical end 222 of the rod between the upper ends of 60 the jaws 216 and 217, causing said jaws to swing about their pivots and to close the lower ends of said jaws on to the hook of the hanger, the pin 223 at this time moving to the lower end of the slot 224.

65 While the jaws are maintained in their hook-gripping positions, the sleeve 213 and the jaws carried thereby are rotated to perform the twisting operation and to form the twist 199.

For thus rotating the sleeve, the gear 238 70 meshing with the pinion portion 237 of the sleeve is provided. Said gear 238 carries the Geneva wheel 239 mounted on the shaft 240 supported in the bracket 231. The Geneva pin 241 is carried by the crank 242 mounted on the shaft 243, 75 also supported by the bearing 231. On the same

shaft 243 is the bevel gear 244 engaging the bevel gear 245 on the shaft 246 (Fig. 2). At its rear end, the shaft 246 carries a suitable sprocket wheel driven by the chain 247, which chain passes about and is driven by a suitable sprocket wheel 5 on the shaft 38.

It will thus be seen that the sleeve 213 is intermittently rotated through the Geneva movement and the driving means therefor just described to perform the twisting operation. After the twisting has been completed, the inner rod 221 is raised whereby the lower end 222 thereof is removed from between the jaws, which jaws are opened by the spring 228, the compression spring 227 aiding in the upward movement of said rod 15 relatively to the sleeve 213. When the rod has been raised sufficiently to cause the pin 223 thereof to engage the upper end of the slot 224, then the sleeve also moves with the rod as a unit to withdraw the jaws from the hanger hook and thereby to free the thus twisted rod for the forwarding thereof by the latches 195 on to the hanger support 193 on the next forward movement of the plate 112.

Said forward movement of the plate 112 not 25 only moves the twisted hanger on to the support 193 but also moves the succeeding hanger into twisting position, as has been hereinbefore indicated so that the parts may be repositioned while the twisting of one hanger is going on for 30 the bending operations upon another hanger, and thereby to permit the machine to work at high speed.

It will be seen that I have provided a machine 35 wherein by the provision of a shuttle drawing wire from two separate rolls, the time during which the shuttle draws a length of wire from one roll is used for the purpose of bending up the wire previously drawn by the shuttle from the other roll. It will also be seen that by providing 40 a separate twisting station, the bending operation upon one wire may proceed simultaneously with the twisting operation upon another previously bent wire and that I have provided a machine designed to automatically produce wire 45 hangers at high speed efficiently and economically.

While I have shown and described a certain specific embodiment of my invention, I do not 50 wish to be understood as limiting myself thereto since I desire to claim my invention as broadly as may be permitted by the state of the prior art and the scope of the appended claims.

I claim:

1. In a garment hanger making machine, 55 means for drawing off and severing lengths of wires alternately from a pair of rolls of wire, means for forwarding a length of wire severed from one roll to a bending station while the succeeding length is being drawn off the other roll, 60 means for bending the wire into a hanger at the bending station while the succeeding wire is being drawn off a roll and severed by said first-mentioned means, means for simultaneously advancing the bent hanger to a twisting station 65 and for ejecting a hanger twisted at the twisting station from the machine, and means for twisting the bent hanger advanced to the twisting station while a succeeding hanger is being bent at the bending station.

2. In a garment hanger making machine, 70 means for alternately drawing off and severing lengths of wire from a pair of rolls including a shuttle and means for reciprocating the shuttle between the rolls, and means for bending a 75

length of wire cut from one roll into a hanger while the shuttle is moving to draw off the succeeding length of wire from the other roll.

3. In a garment hanger making machine, means for alternately drawing off and severing predetermined straight length of wire from a pair of rolls of such wire, means for bending one of such lengths into a hanger while the succeeding length is being drawn off by said drawing off and severing means, and means for forming a twist in the bent length of wire while the succeeding length of wire is being bent by the bending means.

4. In a garment hanger making machine, means for making a pair of first bends, a pair of second bends, a pair of third bends, and a hook bend in a length of wire to bend the wire into a hanger at a single bending station, means for advancing the bent length to a twisting station and for simultaneously ejecting a bent and twisted wire from the twisting station and out of the machine, and means for twisting the wire at the twisting station simultaneously with the bending of a wire at the bending station.

5. In a garment hanger making machine, means for alternately drawing off and severing predetermined lengths of wire from a pair of rolls of wire, means for forming the bends in a length severed from one roll while the succeeding length is being drawn off the other roll and severed, means for transferring the bent wire to a twisting station, and means at the twisting station to twist the neck of the hanger.

6. In a garment hanger making machine, reciprocatory means for gripping, drawing off and severing a predetermined length of wire from a roll on movement of said means in one direction, and means for advancing the severed length to a bending station while the severing means is moving in the opposite direction to position another length of wire for severing from another roll.

7. In a garment hanger making machine, a reciprocatory shuttle, a pair of jaws on said shuttle each adapted to grip one of a pair of wires on the movement of the shuttle in each respective direction, a pair of slideable and rotatable cutters each arranged in the end part of the path of movement of the shuttle in each respective direction, means for opening that jaw which grips a wire at the end part of each movement of the shuttle in either direction to release the gripped wire and for simultaneously engaging and sliding a cutter in the same direction to expose the severed end of the other wire passed through the cutter so moved and thereby to expose said severed end for the gripping thereof by the other jaw, and means for rotating the other cutter to sever the wire released by the first-mentioned jaw.

8. In a garment hanger making machine, means for severing a straight length of wire from a roll, a plurality of spaced recessed fingers each arranged to engage and support the severed wire, means for swinging said fingers simultaneously to carry the wire to a bending station, means at the bending station for forming a pair of symmetrical first bends in the wire, a selected number of said fingers supporting the unbent portion of the wire during the bending thereof and thereby preventing flexure of said unbent portion during the bending of the remainder of the wire, means at the bending station for simultaneously forming a pair of symmetrical second bends and a pair of symmetrical third bends in the upper part of the wire, means at the

bending station for bending the end part of the wire into a hook, means for advancing the bent wire to a twisting station, and means at the twisting station to twist a portion of the wire below the hook bend thereof.

9. In a garment hanger making machine, means for advancing a straight length of wire to a bending station and for supporting the central part of said wire against flexure during the bending operation upon said wire, means at the bending station for simultaneously forming a pair of lowermost symmetrical first bends at the ends of said central part, for then forming simultaneously a pair of second and third bends, and for thereafter forming a hook bend at one end of the wire and thereby completing all the bends of said wire at the bending station, means for advancing the bent wire to a twisting station, and means for twisting that part of the wire below the hook bend thereof at the twisting station while the succeeding length of wire is being bent by said first-mentioned means at the bending station.

10. In a garment hanger making machine, means for advancing a straight wire to a bending station, means at the bending station for forming a pair of first bends in the straight wire and thereby to form a pair of converging end portions on the wire, one longer than the other, means at the bending station for simultaneously forming a pair of second and third bends in said converging end portions comprising a pair of shouldered anvils against which said end portions respectively rest, a cooperating fixed anvil die between said anvils, a pair of reciprocatory strikers, and means for advancing the strikers toward the die to force said end portions into the die and around the anvils, and means at the bending station for bending the end part of the longer end portion of the wire into a hook after said strikers have completed the formation of said second and third bends.

11. In a garment hanger making machine, means for advancing a straight length of wire to a bending station, and means at the bending station for forming a pair of spaced first bends in the wire while maintaining that portion of the wire between the bends straight, said means including a pair of spaced anvil shafts beyond which the wire projects before the bending thereof, a swingable roller mounted on each of the shafts, means for swinging the roller to carry said roller into engagement with the end portion of the wire projecting beyond the anvil shaft and to bend said end portion to an inclined position around the anvil shaft, a finger bent around each of said shafts and having a face normally arranged rearwardly of the wire, a reciprocatory shaft supporting the finger, and means for moving the reciprocatory shaft and the finger carried thereby forwardly to move the wire after it has been bent to a twisting station while said wire is supported by the anvil shafts.

12. In a garment hanger making machine, means for advancing a straight length of wire to a bending station, means at the bending station for forming a pair of spaced first bends in the wire and thereby to arrange the end portions of the wire in upwardly converging relation to each other, a pair of spaced anvils against which said end portions rest after the formation of said first bends in the wire, a die between and cooperating with said anvils, said die being provided with a pair of opposed edge recesses each having a horizontal wall in the same plane as the uppermost

- part of the anvils and having a vertical wall at the inner part of the horizontal wall, and having a rounded fillet joining said vertical and horizontal walls, and a reciprocatory striker arranged 5 for movement in an inclined direction to engage the end portion of the wire and to force said wire into contact with the walls of the recess and thereby to simultaneously form second and third bends in said end portions of the wire.
- 10 13. In a garment hanger making machine, means for advancing a straight length of wire to a bending station, and means at said station for bending said wire into a hanger, said means including means for forming a hook at one end of 15 the wire, said hook-forming means comprising an inner shaft, an outer shaft revoluble about the inner shaft, a roller carried by the inner shaft, a second roller carried by the outer shaft, and means for oscillating said rollers in opposite directions.
14. In a garment hanger making machine, means for advancing a straight length of wire to a bending station, means at the bending station for bending said wire into a hanger, said means 20 including anvils and including surfaces on the anvils arranged rearwardly of the wire, means for reciprocating said surfaces to move said surfaces forwardly to advance the hanger to a twisting station and then to withdraw said surfaces from 25 the wire at the twisting station, means movable into position for additionally supporting the wire at the twisting station, and means for twisting part of the wire during the support thereof by said supporting means.
- 25 15. In a garment hanger making machine having a wire bending station, a pair of wire bending anvils at the bending station, means for reciprocating said anvils toward and from a twisting station, a spring latch carried by and arranged forwardly of each of the anvils, each of 30 said latches being adapted to grip a bent and twisted wire at the twisting station to eject said wire from the machine on the forward stroke of said anvils, and shoulders on the anvils adapted 35 to engage and forward a wire from the bending station to the twisting station on the forward stroke of said anvils, said spring latches yielding on the rearward stroke of said anvils to move rearwardly past the bent wire arranged at the 40 twisting station.
- 40 16. In a garment hanger making machine, means for severing and advancing a wire to a bending station, means at the bending station to bend said wire into a hanger, means for advancing the bent hanger to a twisting station, and means at the twisting station to twist the neck of the bent hanger comprising a pair of pivoted and vertically reciprocating jaws, and means for vertically reciprocating and for oscillating said 45 jaws to close said jaws about the upper end of the hanger at the end of the downward stroke of said jaws and for then rotating said jaws to twist the hanger and thereafter to open said jaws to release the hanger at the beginning of the upward 50 stroke of said jaws.
- 50 17. In a garment hanger making machine for making hangers having a twist therein and having a twisting station, a pair of twisting jaws at the twisting station, a sleeve mounted for vertical 55 reciprocation and having a slot therein, means pivoting the jaws to the sleeve, a rod passing through said sleeve, a pin on the rod entering the slot of the sleeve, means at the extremity of the rod adapted to enter between said jaws to close 60 the jaws upon a hanger when the jaws have been 65 reciprocated into position to grip the hanger, means for rotating said sleeve, and means for reciprocating said sleeve and said rod as a unit during the upper part of the vertical reciprocation thereof and to move said rod and sleeve relatively to each other to alternately close and open the jaws during the lower part of the reciprocation 70 thereof.
- 70 18. In a garment hanger making machine for making hangers having a twist therein and having a twisting station, a pair of twisting jaws at the twisting station, a sleeve mounted for vertical reciprocation and having a slot therein, means pivoting the jaws to the sleeve, a rod passing through said sleeve, a pin on the rod entering the slot of the sleeve, means at the extremity of the rod adapted to enter between said jaws to alternately open and close the jaws, a spring operatively connecting the rod and the sleeve, and means for rotating the sleeve including a Geneva movement, and means for reciprocating the rod to cause said rod and said sleeve to move as a unit during the upper part of the vertical movements thereof and to move relatively to each other during the lower part of the reciprocation 75 thereof.
- 75 19. In a garment hanger making machine, means for alternately drawing off and severing lengths of wire from a pair of rolls including a shuttle, and means for reciprocating the shuttle between the rod, means for advancing the wire to a bending station, means at the bending station for forming a pair of spaced first bends in the wire, said means including a pair of spaced anvil shafts beyond which the wire projects before the bending thereof, a swing roller mounted on each of the shafts, means for swinging the roller to carry said roller into engagement with the end portion of the wire projecting beyond the anvil shaft and to bend said end portion to an inclined position around the anvil shaft, a finger bent around each of said shafts and having a face normally arranged rearwardly of the wire, and a reciprocatory shaft supporting finger, said first bend forming means arranging the end portions of the wire in upwardly converging relation to each other, a pair of spaced anvils against which said end portions rest after the formation of said first bends in the wire, a die between and cooperating with said anvils, a reciprocatory 80 striker arranged for movement to engage each end portion of the wire and to force said wire into said die and thereby to simultaneously form a second and third bend in said end portions of the wire, means for forming a hook at the end part of one of the long portions, said hook-forming means comprising an inner shaft, an outer shaft revoluble about the inner shaft, a roller carried by the inner shaft, a second roller carried by the outer shaft, and means for oscillating said rollers in opposite directions, means for reciprocating said anvils and said fingers toward and from a twisting station, a spring latch carried by and arranged forwardly of each of the anvils, each of said latches being adapted to grip a bent and 85 twisted wire at the twisting station to eject said wire from the machine on the forward stroke of said anvils, and shoulders on the anvils adapted to engage and forward a wire to the twisting station on the forward stroke of said anvils, means movable into position for supporting the wire at the twisting station, and means for twisting part of the wire during the support thereof by said supporting means.
- 90 20. In a garment hanger making machine,

means for alternately drawing off and severing lengths of wire from a pair of rolls including a reciprocatory shuttle, means for advancing a straight severed length of wire to a bending station, means at the bending station for forming a pair of first bends in the wire including a pair of spaced anvil shafts and a swingable roller mounted on each of the shafts, means at the bending station for simultaneously forming second and third bends in the wire including a pair of spaced anvils, a die between the anvils, and a

reciprocatory striker to force the wire around an anvil and into the die, means for forming a hook at one end of the wire comprising an inner and outer shaft and a roller carried by each of said shafts, and means for oscillating said shafts in opposite directions, means for advancing the bent wire to a twisting station, means for supporting the wire at the twisting station, and means for twisting part of the wire during the support thereof by said supporting means.

5

LOUIS BROWNSTEIN.
